(57) **CLAIM**

The ornamental design for a fuel cell power system, as shown and described.

DESCRIPTION

FIG. 1 is a perspective view of a baton fuel cartridge showing our new design;

FIG. 2 is a right side elevation view thereof;

FIG. 3 is a top plan view thereof;

FIG. 4 is a left side elevation view thereof;

FIG. 5 is a bottom plan view thereof;

FIG. 6 is a rear elevation view thereof; and,

FIG. 7 is a front elevation view thereof.

The broken lines shown represent unclaimed subject matter and form no part of the claimed design.
